Int. Cl. D21—02

U.S. Cl. D34—5

FIG. 1 is a front elevational view of a golf putter head showing my new design.

FIG. 2 is an end view of FIG. 1.

FIG. 3 is a top plan view of FIG. 1.

FIG. 4 is a bottom plan view of FIG. 1.

FIG. 5 is a rear elevational view of FIG. 1.

The characteristic feature of my design resides in the combination of the particular club head configuration having a slot across its top vertical to the face and extending downwardly below the midpoint of the face and intersecting a horizontal slot on the face which extends rearwardly almost through the club head that is intersected by another slot parallel to the face that terminates at the top and bottom surfaces of the head.

I claim:

The ornamental design for a golf putter head, substantially as shown and described.
